(57) **CLAIM**

The ornamental design for a head for pipe expander, as shown and described.

DESCRIPTION

FIG. 1 is a front perspective view of a head for pipe expander showing my new design;

FIG. 2 is a rear perspective view thereof;

FIG. 3 is a front elevational view thereof;

FIG. 4 is a rear elevational view thereof;

FIG. 5 is a left side view thereof;

FIG. 6 is a right side view thereof;

FIG. 7 is a top plan view thereof;

FIG. 8 is a bottom plan view thereof;

FIG. 9 is an enlarged view of portion 9 in FIG. 1; and,

FIG. 10 is a front, top and left side perspective view showing the head for pipe expander in a state of use.

The broken lines in FIGS. 1-9 illustrate portions of the head for pipe expander that form no part of the claimed design. The broken lines in FIG. 10 illustrate portions of the head for pipe expander and environmental subject matters that form no part of the claimed design.

The dot-dash broken lines of FIGS. 1 and 9 depicts the limit of the enlarged view and forms no part of the claimed design. The dot-dash lead lines in FIG. 1 labeled 9 indicates the area from which the enlargement in FIG. 9 is taken and form no part of the claimed design.
